W. P. KALFF

SWITCH POINT GUARD

Filed July 25, 1925

INVENTOR
William P. Kalff
BY
Francis E. Boyce
ATTORNEY

UNITED STATES PATENT OFFICE.

WILLIAM P. KALFF, OF HAWTHORNE, NEW JERSEY.

SWITCH-POINT GUARD.

Application filed July 25, 1925. Serial No. 45,989.

To all whom it may concern:

Be it known that I, WILLIAM P. KALFF, a citizen of the United States, residing at Hawthorne, Passaic County, State of New Jersey, have invented new and useful Improvements in Switch-Point Guards, of which the following is a specification.

This invention relates to switch point guards, the object of the invention being to provide a guard of improved construction for protecting railway switch points against wear and tear caused by rubbing contact with the wheels of the equipment, and which guard is retained in operative position without the use of bolts for securing it to the rail.

With the foregoing and other objects in view, the invention consists in the novel features of construction and combination of parts which will be more fully described hereinafter and particularly pointed out in the claims.

In the drawings accompanying and forming part of this specification,

Fig. 1 is a plan view of a portion of a railway switch, illustrating the improved guard applied thereto;

Fig. 2 is a side elevation thereof, looking at the inner side of the rail;

Fig. 3 is a side elevation, looking at the outer side of the rail;

Fig. 4 is a partly sectional end view; and

Fig. 5 is a bottom plan view, on an enlarged scale, of a portion of one of the switch plates formed integral with the guard.

The same characters of reference designate the same parts in the different figures of the drawings.

Referring to the drawings, 1 designates one of the fixed running rails of a railroad track, and 2 the movable switch rail or point adapted to cooperate with the running rail in the usual manner.

My improved switch-point guard comprises a member preferably made integral with a pair of switch plates which pass under and are recessed for the reception of the base of the running rail in the usual manner, said switch plates being provided with openings 5 for the passage therethrough of the usual spikes for securing the plates to the ties 6. The bottom surface of the switch plates is preferably provided with ribs 4^a extending inwardly from opposite side

edges thereof, as shown in Fig. 5, which ribs "bite" into the ties and prevent the gauge of the track from widening at the point of switch. The guard is provided with a horizontal portion 3 the top surface of which, when the guard is in operative position, is flush with the top surface of the rail while the inner side of the guard abuts against the side of the rail and is provided with projections or lugs 3^a adapted to extend under and bear against the underside of the rail head, as shown in dotted lines in Fig. 1 and in full lines in Fig. 4, said lugs thus cooperating with the recess in the switch plates to lock the guard solidly to the rail.

The guard is further provided with a vertical flange 3^b, the form of which is one of the main features of my invention. The side wall of this flange adjacent to the rail is curved outwardly from said rail at its ends, while the entire middle portion thereof is flat, or in a straight line parallel with the running rail. The guard is so disposed with relation to the switch point that the latter overlaps a transverse line passing across one end of said straight portion as clearly shown in Fig. 1. Owing to this peculiar formation of the guard and its particular disposition relatively to the switch point, the guard affords substantial protection to the thin portion of the switch point. In other words, the outer edge of the car or locomotive wheel rubs against the straight portion of the guard and remains in contact therewith until the point of the switch has actually been passed.

For imparting greater rigidity to the guard it is formed with reinforcing webs 95 3^c and 3^d.

I am aware that attempts have been made to produce a device similar to that herein described, but all of such devices with which I am familiar have proved impractical for one reason or another. One of the principal reasons is the fact that no way was found for securing the device in place with sufficient stability, except by bolting it directly to the rail, which was impractical, because at the point where the guard is most needed the switch point is usually provided with a reinforcing member which occupies the space between the head and base of the rail and therefore there is no place at this point for the accommodation of bolt heads or nuts. Another reason for the impracticability of

prior devices with which I am familiar is the fact that the vertical flange was a true arc and the only useful portion thereof, namely, the center point necessarily had 5 to be located so far away from the extreme end of the switch point that it was passed by the wheel before the latter reached the switch point and consequently the effect of the guard was entirely lost. With the present improvement however, because of the manner in which the device is braced against the rail, there is no necessity of bolting it to the rail, and because of the provision of an elongated straight portion on the guard, 10 which portion overlaps a line running transversely across the extreme end of the switch point, the protecting effect of the guard reaches its maximum at the point where it is most needed.

Having thus described my invention, what I claim is:

In railway construction, the combination with a running rail and a switch point disposed adjacent to said rail longitudinally

thereof, of a guard member having a vertical flange extending along said rail and above the same at the side thereof opposite from said switch point, said flange having its wall surface curved at the ends and provided with an elongated portion in a straight line parallel with the rail, the guard being so disposed that said straight portion overlaps a line running transversely across the extreme end of the switch point, a pair of switch plates formed integral with the guard and extending beneath the rail, said switch plates being recessed to receive said rail and to provide a shoulder adapted to engage the inner edge of the rail base, lugs carried by the guard and extending beneath the head of the rail thereby to brace the guard against the rail without the use of bolts, and means for preventing widening of the track gauge at the point of switch.

In testimony whereof I have signed my name to this specification.

WILLIAM P. KALFF.
